LASTS FOR RUBBER SOLED FOOTWEAR

Fred Farmer and Andrew Szerenyl, Waynesville, N.C.,
assignors to Ro-Search, Inc., Waynesville, N.C., a corporation of North Carolina

Original application May 13, 1952, Serial No. 287,536,
now Patent No. 2,830,324, dated April 15, 1958. Divided and this application March 31, 1958, Serial No. 730,738

1 Claim. (Cl. 18—46)

This invention refers to lasts as used for the manufacture of shoes with soles containing rubber. Such a last is shaped to carry the upper and consists commonly of substantial metal parts to withstand the molding pressure. The heel part of the last is often divided from the main part of the last in order to allow the movement of the heel piece nearer to the toe in order to foreshorten the last. In this position the operator can place the upper on the last and by pushing the heel portion with his hand, the last is brought to full size and the upper is ready for the vulcanization of the sole. If the sole is made of porous rubber, it is customary to close and lock the mold by hand using a locking device which is part of the mold.

One object of the invention is to improve such lasts so that it becomes possible to move the heel piece without danger of pinching the upper or its lining between the heel piece and the main portion of the last.

Another object of the invention is to improve the last to permit the mounting of uppers of heavy leather or other less flexible material, which hitherto could not be easily mounted and stretched on the heated metal lasts.

Other objects and characteristics of the invention are clarified in connection with the drawings, which show in Fig. 1 a side view of a last in the extended position according to the invention, while Fig. 2 shows the same last in the foreshortened position.

The last shown in Fig. 1 consists of a base plate 1 carrying a main portion 6 and a movable heel portion 21 with an extension 22 to which a link 25 is pivotally connected. A further link 24 is pivotally connected to the link 25 and an extension 23 of the base plate 7 so as to present a toggle connection. By actuation of the lever 25, the operator's force is multiplied when pulling the movable heel piece 21 into the full size position shown in Fig. 1. The surface separating the heel part 21 from the main part of the heel has the geometric shape of a

2

cylinder surface with the center line 26 located at the instep of the last. This is essential not only because it permits effective foreshortening of the last while in the upper, but also because it permits good fit along the dividing surface and with it good heat transfer from the heated main part of the heel to the part 21.

As the dividing surface maintains its curvature throughout the active part of the last covered by the upper, the surfaces remain in abutting relation during the movement of the heated portion and there is no danger of pinching the upper or its lining in a gap between the heel piece and the main portion of the last. The guiding of the heel piece in a circular path as shown also assures that there is no over-stretching of the upper while moving the heel piece to or from its position in the "full size" last.

As can be seen in Fig. 1, the main part of the last can easily accommodate enough electric heating elements 28 to secure adequate and uniform heating. As the heel piece 21 remains in constant abutting relation, even during its movement, adequate heat transfer to the heel piece is assured.

This application is a division of the application originally filed May 13, 1952, Serial No. 287,536, now Patent No. 2,830,324.

What we claim is:

A last for the vulcanization of rubber soled footwear comprising a main portion corresponding to the upper and the insole of the footwear and a movable heel portion divided from said main portion along a curved surface, the surface having the same curvature throughout the active part of the last so that the heel portion and the main portion are in abutting relation during movement of said heel portion, and toggle means for forcing said heel portion along said curved surface from a position nearer the toe part of the then foreshortened last to the heel location of the then full last, said toggle means comprising a link pivotally connected to said main portion of said last, a second link pivotally connected to said first link and to said heel piece, so as to multiply the operator's force for the moving of said heel piece to its location in the full last.
